UNITED STATES PATENT OFFICE.

JOSEPH B. CLAY, OF CEDAR FALLS, IOWA.

STALL.

1,242,322.

Specification of Letters Patent.

Patented Oct. 9, 1917.

Application filed June 23, 1916. Serial No. 105,380.

To all whom it may concern:

Be it known that I, JOSEPH B. CLAY, a citizen of the United States, residing at Cedar Falls, in the county of Blackhawk 5 and State of Iowa, have invented certain new and useful Improvements in Stalls, of which the following is a description.

My invention belongs to that general class of devices known as stalls, and relates particularly to a stall construction suitable for barns, and particularly for cattle barns. The invention has among its objects the production of a stall of the kind described that is simple, convenient, durable, efficient and 15 satisfactory, and that is attractive in appearance. It particularly has as an object the production of a stall unit that will consist of a minimum of parts, and a construction in which several stalls or units may be 20 combined to afford as many stalls as may be required. The units may be changed from time to time, so that the original installation may be increased or decreased to meet the requirements of the future. It has also as 25 an object the production of a stall construction that will afford comfort as well as safety to the stock, and which may be manufactured at comparatively small cost and used in connection with any other desired equipment. 30 Many other objects and advantages of the construction herein described will be obvious to those skilled in the art from the disclosure herein made.

To this end my invention consists in the 35 novel construction, arrangement and combination of parts herein shown and described, and more particularly pointed out in the claims.

In the drawings, wherein like reference 40 characters indicate like or corresponding parts,

Figure 1 is a perspective view of several units;

Fig. 2 is a sectional view through one of 45 the stalls;

Fig. 3 is a view in elevation of a simple form of clamping member;

Fig. 4 is a section substantially on line 4-4 of Fig. 3;

Fig. 5 is a side elevation of another clamping member, and

Fig. 6 is a section taken substantially on line 6-6 of Fig. 5.

Referring to the drawings, it may be 55 mentioned that I have not endeavored to

illustrate any form of stanchions or other equipment other than a common form of floor and manger construction, in order that the preferred installation of the stall and arrangement might be clearly understood. 60 As was mentioned, my preferred stall may be termed a stall unit, several units being combined to form the desired number of stalls, it being possible to add to or take off units without difficulty. 65

Each unit consists of what may be termed the head or stanchion supporting bar, having one end turned down at 2 to form a supporting leg for that end of the bar. The other end is turned down at 3 to form a 70 relatively short leg, the same being then bent and extended laterally or rearwardly as at 4, either in a straight line or in a series of lines or bends, as illustrated, forming a partition between that stall unit and the 75 next adjacent unit on that side. The rear end of the partition is turned down so as to form supporting legs for the rear end of the partition. Omitting for the present the description of the two end stalls, the 80 intermediate stalls are arranged as shown in Fig. 1, the stalls being secured together by suitable clamping members 6, of any preferred form, or their equivalent for the purpose. The clamping members 6 secure the 85 relatively short leg 3 of one unit to the long leg 2 of the adjacent unit, supporting the relatively short leg as well as securing the units together.

Ordinarily I prefer to make the parts 1, 2, 90 3, 4 and 5 of each unit of an integral piece of pipe or bar, it being obvious, however, that it is not necessary should it be desirable or preferred to form them of separable pieces and unite them with suitable fittings. 95

At the end of the line of stalls, at which the end of leg 2 projects, I provide a partition 7, substantially conforming in design to the partition 4, and having its end turned down as at 8 to support the rear end of the 100 partition, the end partition 7 being secured to the leg 2 by clamp 9. The clamp 9 may be of any desired construction, it being unnecessary to particularly describe the same herewith, inasmuch as the same forms the 105 subject matter of a separate application. (Serial No. 118,500 filed September 5, 1916.) Any equivalent, however, for the type shown may be used. Of course where the end leg 2 is adjacent a wall or other bar- 110

rier, the extra partition 7-8 is not necessary.

The last unit at the opposite end of the row of stalls may be constructed in various ways, this depending to a large extent on the barn arrangement, and whether or not there is a wall or barrier or passageway at the extreme end of the row. I have illustrated the last unit at the opposite end as made up of an inverted U-shaped frame, consisting of the head part or bar 11, and the two legs 12 and 13 formed integral therewith, the leg 12 being clamped to the short leg 3 of the adjoining unit. I have also shown an end partition 7-8 secured to the leg 13 by the clamp 9. This arrangement may be used when there is a passageway at that end of the row of stalls, and where there is no barrier or wall and the side of the stall is desired. I have shown in the dotted lines how the part 11 might be extended and secured at 14 to a wall, or other barrier, in which case the leg 13 and partition shown would be omitted. Obviously, where the relatively short leg 3 of the last unit is adjacent a barrier or wall, that short leg might be supported in any suitable manner.

The stalls may be arranged in place in any desired manner. In Figs. 1 and 2, I show a manger as at 16, a curb 15 and a floor 17, it being understood that the same are constructed as may be desired, and that any suitable material may be employed in constructing the same. The legs and supports of the units shown are embedded in the floor and curb, and in that manner secured in place. If desired the same might be secured in base or socket plates of the usual well known construction, and those secured to the floor.

From the preceding description it will be seen that the stalls are made up of or consist of a minimum of parts constituting an economical construction, as well as one that may be easily installed. There need be no cutting or threading of pipe in installing the units, and there are but few clamps or other fastening devices required. There is likewise a minimum of places where dirt or germs might accumulate, so that the construction is extremely sanitary.

The same is also constructed so that stock will not be injured because of sharp corners or projecting parts. I have not considered it necessary to illustrate any particular type of stanchion to be employed with the stalls when the same are used for stabling cattle, as these may be of any preferred design.

Having thus described my invention, it is obvious that various immaterial modifications may be made in the same without departing from the spirit of my invention; hence I do not wish to be understood as limiting myself to the exact form, construc-

tion, arrangement or combination of parts herein shown and described or uses mentioned.

What I claim as new and desire to secure by Letters Patent is:—

1. A stall unit part comprising a bar bent down at one end to constitute a depending supporting leg, and bent down at the opposite end to constitute a relatively short leg thence bent laterally and thence downwardly at the free end, and means for supporting said relatively short leg. 70

2. A stall unit of the kind described comprising a bar having its ends bent down to provide a long leg and a short leg, the end 80 of said short leg bent laterally and thence downwardly, means secured to said short leg intermediate the ends thereof for supporting the leg, and a bar secured to said long leg intermediate the ends thereof, said bar provided with means at its free end for supporting the same. 85

3. A stall comprising a bar having an extending leg at one side at substantially a right angle thereto, and a short parallel extending leg portion at the opposite side, laterally offset at the end, and thence bent downwardly at the end to form a supporting leg, a coöperating supporting leg and means for securing said coöperating leg to said relatively short leg between the bar and said laterally offset portion, and a partition member provided with means at one end for attaching the same to said first mentioned leg, and means at its other end for supporting the same parallel with said laterally offset portions at the opposite side of the stall. 95

4. A multiple stall construction, consisting of a plurality of units suitably arranged together, each unit consisting of a stanchion supporting bar, a leg integrally connected therewith at one end, and a partition part integrally connected therewith at the other end, and clamping means for connecting the legs of said units with the partition end of the adjacent unit. 105

5. A plurality of stalls, each consisting of a cross bar formed with a leg at one end, with a laterally extending partition at the other end having a support at its end, said stalls being arranged with the cross bars extending substantially in alinement, and means for securing the leg at the end of one stall to the adjacent end of the next stall, 115 the stall at one end having a partition secured to the leg thereat and extending therefrom, substantially similar in contour to the partition formed at the opposite side, and provided with means for supporting its free end. 120

6. A stall construction, comprising the combination of a series of units, each unit consisting of a stanchion supporting bar having an integrally formed leg at one end, 130

with the opposite end bent down, and thence laterally, and thence down to constitute a partition and support therefor, and means for securing the leg of one unit to the bent down portion of the adjacent unit between the bar and partition, whereby the partition side of one unit is supported by the depending leg of the adjacent unit.

7. A stall construction, comprising the combination of a series of units, each unit consisting of a stanchion supporting bar having an integrally formed leg at one end with the opposite end bent down, and thence laterally, and thence down to constitute a partition and support therefor, and means for securing the leg of one unit to the bent down portion of the adjacent unit between the bar and partition, whereby the partition side of one unit is supported by the depending leg of the adjacent unit, and an inverted U-shaped unit at the end of the series, having one leg connected to and supporting the partition end of the next adjacent unit.

8. A stall construction, comprising the combination of a series of units, each unit consisting of a stanchion supporting bar having an integrally formed leg at one end with the opposite end bent down, and thence laterally, and thence down to constitute a partition and support therefor, and means for securing the leg of one unit to the bent down portion of the adjacent unit between the bar and partition, whereby the parti-

tion side of one unit is supported by the depending leg of the adjacent unit, and an inverted U-shaped unit at the end of the series, having one leg connected to and supporting the partition end of the next adjacent unit, and a partition carried by the end leg of the unit at the opposite end of the series.

9. A stall construction, comprising the combination of a series of units, each unit consisting of a stanchion supporting bar having an integrally formed leg at one end with the opposite end bent down, and thence laterally, and thence down to constitute a partition and support therefor, and means for securing the leg of one unit to the bent down portion of the adjacent unit between the bar and partition, whereby the partition side of one unit is supported by the depending leg of the adjacent unit, and an inverted U-shaped unit at the end of the series, having one leg connected to and supporting the partition end of the next adjacent unit, and partitions connected to and carried by the legs at the two extreme ends of the series.

In testimony whereof, I have hereunto signed my name in the presence of two subscribing witnesses.

JOSEPH B. CLAY.
